DESIGN FOR AN EARRING

Mary C. Martindale, New York, N. Y.

Application March 22, 1940, Serial No. 91,143

Term of patent 7 years

To all whom it may concern:

Be it known that I, Mary C. Martindale, a citizen of the United States, residing at New York city, in the county of New York, and State of New York, have invented a new, original, and ornamental Design for an Earring, of which the following is a specification, reference being had to the accompanying drawing, forming a part hereof.

In the drawing—

The single figure is a perspective view of an earring showing my new design.

The essential features of my design reside in the particular arrangement of the monogram in combination with the earring as shown, it being understood that the initial shown are for illustrative purposes and that other combinations of three initials may be used.

I claim:

The ornamental design for an earring, as shown and described.

MARY C. MARTINDALE.
